UNITED STATES PATENT OFFICE.

EDWIN E. SLICK, OF WESTMONT, PENNSYLVANIA.

COMPOUND RAIL.

1,125,748.

Specification of Letters Patent.

Patented Jan. 19, 1915.

Application filed November 12, 1913. Serial No. 800,430.

To all whom it may concern:

Be it known that I, EDWIN E. SLICK, a citizen of the United States, residing in the borough of Westmont, in the county of Cambria and State of Pennsylvania, have 5 invented certain new and useful Improvements in Compound Rails; and I do hereby declare the following to be a full, clear, and exact description of the invention, such as 10 will enable others skilled in the art to which it appertains to make and use the same.

My invention relates to railroad rails with special reference to a rail made of two portions, the wearing portion being provided 15 with two heads, so that when one is worn out it may be turned over and the other one used. I also prefer to make the wearing portion of my compound rail of very hard steel which is well adapted to withstand the 20 service to which it is put, while I also prefer to make the base portion of structural or medium steel, which, on account of its 25 toughness and ease of working, is well adapted for its particular portion of the service.

In order that the two parts of my compound rail may be produced by the process of rolling and at the same time be such as to fit tightly together, I provide the web of 30 my base portion with a projection which has an inclination at its lower side and a head portion of greater width which is also inclined. The projection on the web of the base member is adapted to contact with a 35 correspondingly inclined projection on the wearing member, and the inclined top of the head of the base member is adapted to support the correspondingly inclined portion of the head of the wearing member. 40 The two parts being in contact as described, they are secured firmly together by large bolts or rivets which pass through the web portions of each member at frequent intervals. On account of the inclined surfaces 45 just described, the action of the bolts or rivets in drawing the two parts together has a wedging and tightening effect, so that the head portion of the wearing member is pressed very firmly against the correspond- 50 ingly inclined head portion of the base member and as clearances are provided between the webs of the two members, the two portions can be drawn together more tightly from time to time, if required. I also prefer to stagger the joints in the two portions 55 of my compound rail in order that the ac-

tion and strength of the same may be substantially continuous in effect and where the base members are joined, I prefer to provide an angle splice bar fitting on the outer side 60 of the track.

Having thus given a general description of my invention, I will now, in order to make the matter more clear, refer to the accompanying sheet of drawings which forms 65 part of this specification and in which like characters indicate like parts:

Figure 1 is a side elevation of my compound rail, this view being taken on the outside of the track and showing the ties 70 and ballast on which the rails are supported. Fig. 2 is a cross sectional elevation on an enlarged scale taken on the line II—II of Fig. 1, looking in the direction of the 75 arrows.

Referring now to the numbers of reference on the drawings:—1 represents the base portion in general, 2—2 the base flange thereof, 3 the web, 4 the head, 5 the inclined upper surface of the head, and 6 a projection or locking strip on the web provided with an inclined lower face as shown. The locking strip 6 may have its lower surface substantially at right angles to the web 3 but I prefer to make it inclined as shown, 85 as it thus co-operates with the upper inclined surface 5 of the head 4 to maintain the wearing portion in proper relative position.

7 is a projection on the upper portion of the 90 base member. Slight clearances 8 and 9 are originally provided between the projecting portions of the base member and the adjacent portions of the wearing member. The heads of the wearing member are indicated as 10 95 and are provided with inclined surfaces 11—11 as shown, and the lower sides of the head 10 are also provided with inclined surfaces 12, either of which is adapted to fit closely to the upper inclined surface 5 of the 100 base member.

At and near the junctions of the two base members I provide an angle splice bar which is generally represented as 13 provided with a base member 15 adapted to fit the lower 105 flange of said base member, a web 14 and a head portion 16 adapted to fit under the head portion of said base member. The two portions of my compound rail are held firmly together by means of the bolts 17 pro- 110 vided with the nuts 18, or these may be otherwise secured by rivets or similar

means. My outside splice bar 13 is secured to the rails by means of the bolts 19 and nuts 20 as shown. The space between the abutting ends of my base members is indicated as 21 and the space between the abutting ends of my wearing member is indicated as 22.

In practice the rails are assembled together in positions shown and when, after reasonable use, the upper head 10 is worn to the allowed limit, the bolts or rivets securing the portions together are withdrawn, the wearing member is turned upsidedown and the other head 10 thereof, which is not worn, is placed in the upper position ready for use.

I prefer to design my compound rail in such a manner that the base member is substantially as strong as the present standard rails and the wearing member therefore adds strength to the combination, besides which the wear of said wearing member does not reduce the strength of the compound rail as low as that of the present standard rails.

It should also be noted that my wearing member is of substantial depth with a comparatively thin web and large heads, thus providing a section with a large moment of inertia, thus adapting it to withstand heavy stresses.

It should be particularly noted that the projection 11 on the wearing member is adapted to contact with a corresponding projection on the web of the base member and at the same time the inclined surface 12 of the head portion of the wearing member is adapted to contact with the upper and similarly inclined surface of the head portion 4 of the base member. The parts being in this position, the tightening of the bolt 17 tends to draw the two parts of the rail together with great firmness and as no rolled sections can be made mathematically perfect, this method of construction insures a tight fit of the parts at all times so that they will act in perfect unison.

Although I have shown and described my improvements in considerable detail, I do not wish to be limited to the exact and specific details shown and described, but may use such substitutes, modifications or equivalents thereof, as are embraced within the scope of my invention, or as pointed out in the claims.

Having thus described my invention, what I claim and desire to secure by Letters Patent is:—

1. A compound rail having a base portion, provided with a head, a web and a base flange, a locking strip projecting from said web below said head, a double headed wearing portion provided with projections adapted to contact with the lower side of said locking strip, the underside of the head

of said portion being adapted to rest upon the head of the base portion, the wearing portion and the base portion being primarily spaced apart laterally to give adjusting clearance, and means for securing the same together.

2. A compound rail comprising a base portion provided with a web, a base flange and a head, a tapered locking strip projecting from said web below said head, a wearing portion comprising a web with head portions projecting oppositely from the extremities thereof, said head portions being provided with tapered projections adapted to contact with the lower side of said tapered locking strip, and means passing through the webs aforesaid adapted to secure the parts together.

3. In a railway rail of the class described, a base portion provided with a head having an inclined upper face, a web portion with a projection extending therefrom below said head, a wearing portion provided with a web and heads extending in opposite directions from the extremities thereof, the lower surfaces of said heads being inclined to conform to the inclination of the head of the base portion, and means for securing the two portions together.

4. A compound rail comprising a base portion provided with a head the upper face of which is inclined and a web provided with a projection extending therefrom below said head, a wearing portion provided with a web and corresponding projections adapted to cooperate with the first-named projection and a pair of heads extending oppositely from the extremities of said web, the wearing portion and the base portion being primarily spaced apart laterally to give adjusting clearance, and means passing through the webs of each portion adapted to firmly secure the same together.

5. A compound rail comprising a base portion provided with a tapered clamping surface, a wearing portion provided with a corresponding tapered clamping surface adapted to contact therewith, and means for securing the two portions together, and a space intermediate the base portion and wearing portion below the clamping surfaces and adjacent the securing means.

6. A compound rail comprising a base portion provided with a head, a web and a base flange, tapered clamping surfaces on said web and head, an unsymmetrical double headed wearing portion provided with a web and heads extending oppositely from the extremities thereof, tapered clamping surfaces on said wearing portion adapted to contact with the corresponding tapered surfaces of the base portion, and means passing through the web portions adapted to secure the parts together.

7. A compound rail comprising a base

portion provided with a web, a base flange and an inclined head, a locking strip projecting from the web thereof, a wearing portion comprising a web and two heads 5 extending from opposite sides of the extremities thereof, the under surfaces of said heads being inclined to correspond with the inclination of the head of the base portion, clamping surfaces provided on said head portion adapted to coöperate with the locking strip and inclined head aforesaid, said portions being secured together by means passing through the webs thereof, the joints in said base members and wearing 10 members being staggered.

8. A compound rail comprising a base portion provided with a web, a head and

a base flange, tapered clamping surfaces on said base portion, a head portion provided with a web and heads projecting oppositely 20 from the extremities thereof, tapered clamping surfaces on said wearing portion adapted to coöperate with the corresponding surfaces of the base portion, and means for securing the parts together, in combination 25 with a splice bar adapted to secure and join the abutting ends of said base portion.

In testimony whereof I hereto affix my signature in the presence of two witnesses.

EDWIN E. SLICK.
